UNITED STATES PATENT OFFICE.

WILLIAM R. CHITTENDEN, OF CHICAGO, ILLINOIS.

MECHANICAL MOVEMENT.

1,211,409.

Specification of Letters Patent.

Patented Jan. 9, 1917.

Application filed August 20, 1915. Serial No. 46,450.

To all whom it may concern:

Be it known that I, WILLIAM R. CHITTENDEN, a citizen of the United States, and a resident of the city of Chicago, in the county 5 of Cook and State of Illinois, have invented a certain new and useful Improvement in Mechanical Movements; and I do hereby declare that the following description of my said invention, taken in connection with the 10 accompanying sheets of drawings, forms a full, clear, and exact specification, which will enable others skilled in the art to which it appertains to make and use the same.

My invention relates generally to improvements in mechanical movements and it consists, essentially, in the novel and peculiar combination of parts and details of construction, as hereinafter first fully set forth and described and then pointed out in 20 the claims.

While in its essentials my invention is adapted for the crushing of rock in general and the reduction of quartz and adobe ore in particular, still the said invention is capable of much wider application in its ramifications as will more fully appear.

Broadly speaking, I employ a rocker bed adapted for oscillation upon a substantially plain surface. Erected upon the rocker bed 30 are a pair of perpendicular arms, at the outer ends of which are pivoted a shaft parallel or substantially so, to the rocker bed between said arms, and, suspended from said shaft is carried an oscillatable weight. The 35 rocker bed already mentioned is of an arc having its center coinciding with the center of said shaft, so that if said arms be oscillated at their upper ends a shifting of the axis of oscillation of the suspended weight is 40 caused to take place; a rocking motion of the bed plate induced, and a decided oscillatory motion of the suspended weight created. The reciprocation of the perpendicular arms of the rocker bed will restore the moving 45 inertia of the suspended weight and will maintain its oscillation thereof within certain limits.

In the drawings hereinbefore referred to and made a part hereof, Figure 1 is a vertical, longitudinal section of my invention, taken on line 1—1 of Fig. 2, the extreme oscillation of the rocker bed and its perpendicular arms and the suspended weight being shown in dotted lines. Fig. 2 is a vertical

cal, transverse section of my invention on line 2—2 of Fig. 1. Fig. 3 is a transverse, vertical section of a fragment of my invention on line 3—3 of Fig. 1. Fig. 4 is a like section on line 4—4 of Fig. 1, showing the section of the rocker bed plate in full section 60 instead of dotted lines as in Fig. 1. Fig. 5 is an end elevation of my invention disclosing mechanical means for reciprocating the rocking arms forming part of my disclosure, and Fig. 6 is, in part, an elevation and, in 65 part, a section of the same on line 6—6 of Fig. 5. Fig. 7 denotes a schematic fragmentary side view, showing a modified form of mechanical rocking means.

Like parts are designated by corresponding symbols or characters of reference in all the figures of the drawings.

In the preferred mode of carrying out my invention, there is employed a preferably rectangular base frame A having side walls 75 B and B', medially of the length of which are provided vertical slots C and C' for purposes hereinafter more fully set forth. The said base frame has end walls D and D', Fig. 1, which are of lesser height than the 80 side walls B and B', and has an open interior through the same, vertically. Surrounding the interior faces of the side walls B and B' and D and D', at a proper elevation, are ledges or lips 10 and 10^a and 11 and 85 11^a and a transverse rib 12, upon which ledges or lips rest a plurality of crushing plates 13, which plates are preferably plain upon their upper surface, both longitudinally and transversely and are a snug fit 90 upon the ledges aforesaid, between the walls B and B' and D and D', to prevent movement thereof in said frame A.

Adapted for a rockable and slight endwise movement upon the crusher plates 13, within 95 the confines of the side walls B and B' and D and D', is located a rocker bed E having medially of its length, upon its opposite sides, rollers F^a, pivoted upon studs G^a, which rollers are constructed for upward movement 100 in the slots C and C' already referred to. Arising perpendicularly from the said rocker bed E, medially of its length, and from opposite sides thereof are arms F and F', which arms are secured at their lower 105 ends to said rocker bed E, and at their upper extremities are pivoted to a transverse shaft G. The lower surface of this rocker

bed is arcuate, having its center coinciding with the axis of said shaft G; and this arcuate surface, rolling on the plane surface of the crusher plate 13, wagon wheel fashion, as it were, will cause the upper ends of said upright arms F, F', to reciprocate, or swing, like an inverted pendulum, as will herein-after more fully appear.

Suspended from the shaft G by means of a rod or bar H, there is a weight J, which is adapted to oscillate between the perpendicular arms F and F', and to be guided in its travel by upright sides E' and E'' of the rocker bed E as clearly seen in Figs. 1, 2, 3 and 4.

Arising from the four corners of the base member A are four posts 50 and 60, the said posts 50 and 60 being connected together by horizontal, longitudinal braces 51 and 52 at the upper end of said posts and by like braces 53 and 54, intermediate the height of said posts, the same being provided to maintain said posts 50 and 60 in an upright, parallel position with respect to each other.

Laterally connecting the posts 50 with the posts 60 are braces 55 and 56 located at the upper end of said posts and intermediate the height of said posts are like braces or bars 55^a and 56^a, the whole forming a well connected upstanding structure.

Extending horizontally between the upright posts 60 or the uprights 50, if desired, along or near the upper edges thereof, is located a horizontal platform 61, and on the side adjacent the inner edge of this platform 61, the perpendicular member F' or the member F, if desired, is extended upwardly to a proper height to provide a handle member 62, whereby the said perpendicular member 60 and its corresponding members F or F', as the case may be, may be reciprocated by a person located or stationed upon said platform 61. It will thus be observed that a person stationed upon the platform 61 may by properly manipulating the handle 62, oscillate the bars F, F', and thereby also cause the oscillation of the weight J and to maintain the latter in constant oscillation by a mere moving of the handle 62 in an evident manner.

The crushing plates 13, lodged on the lips 10, 10^a, 11 and 11^a on the interior of the rectangular base A, are provided with a series of perforations 70, these perforations being of largest diameter near the ends D and D' of the ends of the base frame A and gradually decreasing in size toward the longitudinal center of said frame, as at 71. And, perforating the sides B and B' near the ends D and D' are openings K, supplied with chutes L, through which material to be crushed is permitted to flow upon the upper surface of the crusher plates 13; and it is here pointed out that the side wings E' or E'', stop the flow of such material upon said

surfaces when the outer ends of the rocker plate E approach contact with the crushing plate 13.

It is evident that the chutes L may be connected with a common material hopper (not shown) whereby the material passing through said chutes may be fed thereto, or, if the material be in a pile, shovels may transmit the same from said pile or piles to said chutes. It is likewise obvious that as the material to be crushed flows upon the top face of the crusher plates 13, the forward and backward movement of the rocker bed E, induced by the oscillation of the weight J, will crush rock located between said bed E and crusher plates 13, and will force the same through the openings 70, 71 to screens below, (not shown) wherein the crushed stone may be properly screened and delivered to suitably located bins.

Attention is now directed to the fact that the entire weight of the rocker bed E, its perpendicular arms F and F'; the suspending rod H, and the oscillating weight J, is effective as a crushing weight for the material upon the crushing plates 13, and all that is necessary to maintain the oscillation of the weight J, is the movement of the axis of oscillation thereof from X to Y, Fig. 1, by a person manipulating or moving the upper end or handle 62 from one extreme to the other, the limit of oscillatory or vibratory movement of the arms F and F' being controlled by stops 99 and 99^a on the longitudinal members 51 or 52, as clearly shown in Fig. 1.

If it be desired to pulverize the material to a fine state of disintegration, I discard the series of holes 70 of the crushing plates 13, and retain only the openings 71 located near the center of said crushing plates, so that the repeated rockings of the rocker bed E will "pull", as it were, the granulated material toward the openings 71, by which time the material to be crushed, has been reduced to a fine dust.

Hereinbefore I have disclosed a device in which the axis of oscillation of the weight J has been shifted in a horizontal plane by hand power, but in Figs. 5, 6 and 7, I disclose means whereby the said axis may be shifted by mechanical means; one case, that of Figs. 5 and 6 disclosing means whereby the axis of oscillation of the weight J may be reciprocated under and controlled by the vibratory movement of the perpendiculars F and F' of the rocking bed E, and in Fig. 7, disclosing a means, whereby the said perpendiculars F and F' and the rocking bed E may be controlled by the oscillation of the freely swinging weight J. And I now wish it understood that the vibration of the arms F and F' may be accomplished by other means than those shown in Figs. 5, 6, and 7. For instance, solenoid coils and

cores with proper electrical connections may be substituted for the steam cylinders and mechanism disclosed in said figures without departing from the spirit or scope of my invention. And, moreover, arms extending longitudinally beyond the ends of the rocker bed E and connected to proper motive power means may be employed to impart the proper movement to the said rocker bed and the requisite oscillation to the weight J, through the required shifting of the axis of oscillation of the said weight J by reciprocating the ends of the perpendicular arms F and F'.

As an illustration of the employment of my device may be mentioned the use as a coffee grinder or crusher in coffee stores and the like, in which instance the bed frame A, with its chutes L, and its crusher plates 13 with certain of the openings 70 or 71 are employed. The rocker bed E and its rollers F^a and studs G^a, together with the suspended weight J, freely depending from the shaft G, the latter journaled at the upper end of the arms F' and F are essentials. By an occasional movement of the hand at the handle end or member 62 of one of the arms F or F', a sequential shifting of the axis of oscillation of the weight J is obtained, and the swinging, oscillation, or pendulum motion of the weight J is maintained, and, a crushing action between the rocker bed E and the top surface of the crushing plates 13 is secured.

I have already mentioned that the rocker bed E has a compound rocking, and endwise movement. This endwise movement is attained by the rollers F^a, moving vertically in the guiding slots C, C'. As the bed E rolls on the crusher plate 13, the center of rotation of the bed would naturally shift either to the right or to the left, as the case may be; but on account of these rollers F^a moving in said slots C, C', this reciprocating movement or shifting of the center of rotation is translated into a vertical movement thereof, which causes a slight dragging or scraping movement of the curved surface of the rocker bed on the horizontally disposed plane surface of the crusher plate 13, which movement materially assists in disintegrating the material placed between these two surfaces, and in moving the said material from the ends of the crusher plate toward the center thereof.

In Figs. 5 and 6 are illustrated means for mechanically shifting the arms F and F', to reciprocate the axis of oscillation of the weight J, the said movement being controlled by a lever 100, pivoted at one end to the frame work of the machine and with the other end slidably embracing the shaft G, the said lever being alternately acted upon by pistons 101 and 102 of cylinders 103 and 104, which pistons are controlled

by valves 105 and 106, actuated by a bar 107, having stems 108 and 109, which are alternately engaged by the vibration of the lever 100 in an evident manner.

In Fig. 7 is shown the suspension rod for the weight J as a solid bar H', having an upwardly projecting arm H'', which is adapted to control the valves of the cylinders 106 or 105, instead of the same being directly controlled by the lever 100. By this construction the oscillation of the weight J controls the shifting of the axis of oscillation of said weight in a manner readily understood.

While I have herein disclosed in detail the mode of practising my invention, I do not hereby limit myself to the particular structure described, and reserve to myself the right to make such changes in structure and detail as may be permitted under a broad interpretation of the claims herewith appended.

I have hereinbefore disclosed the preferred mode of practising my invention, but I reserve the right to make such and any changes as might occur to one skilled in the art to which this invention appertains, or to make any and all such alterations as may be permitted under the doctrine of equivalents.

Having thus fully described my invention I claim as new, and desire to secure to myself by Letters Patent of the United States:—

1. A device of the class described, comprising, a plane plate, a curved base, a pair of upstanding arms secured to said base, means connecting said arms at their free ends, a freely swinging weight suspended from said connecting means, and means for shifting the axis of oscillation of said weight.

2. A device of the class described, comprising a horizontally disposed plane plate, a curved base, a pair of upstanding arms secured to said curved base, a shaft connecting the upper ends of said arms, a freely swinging weight suspended from said shaft, means for laterally moving said shaft to cause the oscillation of said weight.

3. A device of the class described, comprising a curved bed, a pair of upstanding arms secured to said bed, means for connecting the upper ends of said arms, a freely swinging weight suspended from said connecting means, and means for horizontally shifting the axis of oscillation of said weight.

4. A device of the class described, comprising, a pair of upstanding arms, a curved base to which said arms are attached at their lower ends, a freely swinging weight suspended from the upper ends of said arms, and means for oscillating said weight by a reciprocating movement of the upper ends of said arms.

5. A device of the class described including, in combination, a rockable bed and perpendiculars arising therefrom, a member connecting said perpendiculars, a weight freely suspended from said member, and means whereby said bed may be oscillated.
6. In combination, a rockable bed, a frame supporting said bed, and guiding the same, alined perpendiculars arising from said bed, means connecting said perpendiculars, a freely suspended weight depending from said connecting means, and means for oscillating said perpendiculars.
7. In combination, a rockable bed, guiding means for said bed, a frame for supporting said bed, alined, upstanding arms secured to said bed, connecting means for said arms, a freely suspended weight connected to said arms, and means for reciprocating said arms.
8. In combination, a supporting frame, said frame having vertical guides, a rockable bed, said bed having an arcuate lower surface, a crushing bed on which said rockable bed is constructed to roll, upstanding arms secured to said bed, and an oscillatable weight suspended from said arms.
9. In combination, a supporting frame, having vertical guides, a rockable bed operating in said guides, upstanding arms on said rockable bed, oscillatable means connecting said arms at their upper ends, an oscillatable weight freely suspended from said connecting means, and means for imparting movement to said arms.
10. In combination, a supporting frame having vertical guides, a rockable bed operating between said guides, upstanding arms on said rockable bed, oscillatable means on said arms connecting said arms adjacent their upper ends, an oscillatable weight suspended from said connecting

means, and means for imparting reciprocating movement to said arms at their upper ends.

45

11. In combination, a bed frame, a superstructure thereon, a rockable bed on said frame, upstanding members secured to said rockable bed, said members being in spaced relationship, a freely suspended weight between said members, a link in said superstructure, said link being connected to said members, and means for imparting movement to said link.

50

12. In combination, a bed frame, a superstructure thereon, a rockable bed in said frame, upstanding, connected, members on said rockable bed, a freely suspended weight oscillatable between said members, a link in said superstructure, said link being connected to said members, and means for imparting forward and backward movement to said link.

55

13. A device of the class described including, in combination, a rockable bed and perpendiculars arising therefrom and a member connecting said perpendiculars, a weight freely suspended from said connecting member, and means shifting said perpendiculars, whereby the axis of oscillation of said weight is changed.

60

14. A device of the class described including, in combination, a rockable bed and perpendiculars arising therefrom and a member connecting said perpendiculars, a weight freely suspended from said connecting member and means oscillating said perpendiculars, whereby the axis of oscillation of said weight is reciprocated.

65

In testimony that I claim the foregoing as my invention, I have hereunto set my hand.

70

WILLIAM R. CHITTENDEN.
